US00D812931S

(12) **United States Design Patent** (10) **Patent No.:** **US D812,931 S**
Chen et al. (45) **Date of Patent:** **** Mar. 20, 2018**

(54) **PILLOW**

(71) Applicant: **SHENZHEN LIAN DA TECHNOLOGY INDUSTRIAL CO., LTD.**, Shenzhen, Guangdong (CN)

(72) Inventors: **Congyu Chen**, Guangdong (CN); **Congchao Chen**, Guangdong (CN)

(73) Assignee: **Shenzhen Lian Da Technology Industrial Co., Ltd.**, Shenzhen (CN)

(**) Term: **15 Years**

(21) Appl. No.: **29/592,434**

(22) Filed: **Jan. 30, 2017**

(51) LOC (11) Cl. **06-09**

(52) U.S. Cl.

USPC **D6/601**

(58) **Field of Classification Search**

USPC ..... D6/333, 349, 355, 375, 388, 512, 563, D6/564, 611, 707, 715, 716, 716.1, D6/582-583, 587-592, 595-609, D6/617-622; D24/183-185, 234, 178, D24/180, 181, 189; D21/803, 804, 805, D21/809, 599; 5/401, 420, 600, 630, 5/631, 632, 633, 635, 636, 638, 639, 646, 5/652, 652.1, 655, 703, 730; 297/1, 2, 4, 297/93, 180.11, 195.1, 195.11, 195.13, 297/393, 397, 452.12, 452.14, 452.15, 297/452.21, 452.24, 452.26, 452.48, 297/452.62, 482; D2/719, 725, 734, 741 CPC A47G 9/10; A47G 9/1009; A47G 9/1027; A47G 9/1045; A47G 9/1063; A47G 9/1072; A47G 9/1081; A47G 9/00; A47G 2009/001; A47G 2009/002; A47G 2009/003; A47G 2009/005; A47G 2009/006; A47G 9/02; A47G 9/0207; A47G 9/0215; A47G 9/0223; A47G 9/023; A47G 9/0238; A47G 9/0246;
